US0D1003887S

(12) **United States Design Patent** (10) **Patent No.:** **US D1,003,887 S**
Srour (45) **Date of Patent:** **** Nov. 7, 2023**

(54) **GRIPPING APPARATUS FOR PORTABLE ELECTRONIC DEVICE**

(71) Applicant: **Quest USA Corp.**, Brooklyn, NY (US)

(72) Inventor: **Ikey Srour**, Brooklyn, NY (US)

(73) Assignee: **QUEST USA CORP.**, Brooklyn, NY (US)

(**) Term: **15 Years**

(21) Appl. No.: **29/806,355**

(22) Filed: **Sep. 2, 2021**

(51) **LOC (14) Cl.** **14-06**

(52) **U.S. Cl.**

USPC **D14/251**

(58) **Field of Classification Search**

USPC D14/217, 250–253, 440, 447; D12/415; D3/218

(57) **CLAIM**

The ornamental design for a gripping apparatus for portable electronic device.

DESCRIPTION

FIG. 1 is a perspective view of a gripping apparatus for portable electronic device showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof; and,

FIG. 7 is a right side elevation view thereof.

Broken lines illustrate portions of the gripping apparatus for portable electronic device that form no part of the claimed design.

1 Claim, 5 Drawing Sheets
